UNITED STATES PATENT OFFICE.

HENRY J. RICHARDS, OF BROOKLYN, NEW YORK.

TELEPHONE ATTACHMENT.

1,334,319.

Specification of Letters Patent. Patented Mar. 23, 1920.

Application filed May 12, 1917. Serial No. 168,279.

To all whom it may concern:

Be it known that I, HENRY J. RICHARDS, a citizen of the United States, and a resident of Brooklyn, county of Kings, and State of New York, have invented new and useful Improvements in Telephone Attachments, of which the following is a specification.

This invention relates to telephone attachments and has for its object to provide an attachment for connection to an ordinary desk telephone which will support the receiver in a position to be closely adjacent the user's ear when talking into the transmitter, whereby both hands of the user may be free and the annoyance and fatigue of holding the receiver for long periods are avoided.

A further object of the invention is to provide a device of this character embodying a holder for the receiver which may be adjusted in various directions to secure a positioning of the receiver best suited for the user of the particular instrument.

A further object of the invention is to provide a device of this kind in which the receiver is permanently supported in its position for use and the contact-controlling hook upon which the receiver is ordinarily suspended is controlled by a trip designed to engage and hold the receiver hook down when the latter is pressed down, but not to interfere with or exert a pressure upon the hook when the trip is released.

A further object of the invention is to provide a device of the character described in which all the parts are supported from a single bracket adapted to be clamped to the neck of the transmitter support to a position where the attachment does not interfere with the adjustment of the transmitter or the proper use of the instrument.

A further object of the invention is to provide a device of this character whose parts may be made in quantity by machinery with little hand labor, and which is of low manufacturing cost.

A further object of the invention is to provide an attachment of this class which shall be adjustable to fit telephone instruments of various styles and sizes with the use of only one interchangeable part.

With the above objects in view, my invention consists of the construction shown in the accompanying drawings and herein-after described, it being understood that

the construction disclosed is a preferred embodiment of the invention, but its design may be variously modified without departing from the spirit of the invention or the scope of the appended claims.

In said drawings:

Figure 1 is an elevational view of a telephone equipped with my attachment;

Fig. 2 is a plan view of the telephone shown in Fig. 1 with portions broken away;

Fig. 3 is a detached view of a portion of the attachment adjacent the telephone instrument;

Figs. 4 and 5 are detail views showing the method of adapting the attachment for telephones of different styles; and

Fig. 6 is an elevational view showing the attachment adapted for wall telephones.

Fig. 7 is a view at right angles to Fig. 6.

Referring to the drawings, 1 indicates the bracket by which the attachment is connected to the telephone. The bracket comprises a clamping collar 2 here shown as a part hinged to the main part of the bracket with a screw for clamping the hinged part to the bracket on the side opposite the hinge, the inner face of the hinge and the opposite face of the bracket part being lined with felt or other suitable material to secure a tight grip on the neck of the mouth-piece of the telephone without marring it.

The bracket extends beyond the clamping screw in the form of an arm in which is fixedly supported, by brazing or otherwise, a vertical tubular bearing 3 in which the arm 4 carrying the receiver support 5 is swiveled for adjustment in a horizontal plane. The arm 4 is preferably formed of a rod of metal light enough in weight for its curve to be altered by manual effort, but stiff enough to rigidly support the receiver once the proper adjustment of the arm is secured. The lower end of the arm is turned to fit the tubular bearing 3 and the latter is provided with a set-screw 6 by which the arm may be clamped in the desired position of horizontal and vertical adjustment, the set-screw being preferably set in the wall of the bracket to secure an additional depth of thread.

Above its lower swiveled portion the arm 4 is curved outwardly to extend in a substantially horizontal direction from the bracket and is of proper length to support the receiver at a point sufficiently remote

from the transmitter for the receiver to come adjacent the ear of the user when talking on the telephone.

The arm 4 is preferably provided with 5 hooks 11 through which the telephone cord is strung. When the holder is supplied with the telephone, the cord may be materially reduced in length and may also, if desired, be connected to the instrument at the stem 10 adjacent the bracket instead of at the base.

The holder 5 for the receiver comprises a cradle of resilient metal into which the receiver may be sprung in the manner indicated, and which will clamp it firmly in position. The cradle is swiveled to the end of the arm 4 by means of a screw and clamping nut 6 so that the angle of the receiver to the direction of the arm may be adjusted as desired.

20 In order that the weight of the receiver when supported beyond the base of the telephone will not make the telephone liable to be easily overturned, the bracket 1 is weighted, the weight 7 in the construction shown 25 consisting of a knob of lead which is fixedly soldered or otherwise attached to the lower end of the vertical bearing 3 of the supporting arm.

As previously explained, the receiver is to 30 be supported in the cradle at all times and not returned to the usual supporting hook when the telephone is not in use. In order to control the operation of the hook there is provided a trip pivoted to the bracket 1 in 35 a bifurcated lug 9 projecting from the side of the bracket at right angles to the support for the arm 4, the bracket being clamped to the telephone in a position over the receiver hook.

40 The trip 8 comprises a threaded sleeve 10 having a lug projecting from one side by means of which it is swiveled to the bifurcated projection 9, and threaded in the sleeve is a trip arm 12 whose lower end is 45 shaped to engage the upper face of the receiver hook to hold the latter down when the telephone is not in use.

The trip arm is adjusted in the threaded sleeve 10 to such position that when the 50 lower horizontal portion of the trip arm which rests on the top of the receiver hook is turned to a position almost vertically under the pivot screw, the receiver hook will be held in its lowermost position. The action is in effect a toggle action; the pressure from the spring of the receiver hook being substantially in line with the axis of movement has little or no tendency to turn the trip on its pivot, so that the frictional 55 engagement of the receiver hook on the telephone of the trip arm is ample to hold the parts in position. The trip arm is locked in its adjusted position by means of clamping nuts on the threaded shank of the trip 60 arm at each end of the sleeve 10.

The operation of the device will now be described. After the bracket is clamped in place on the neck of the telephone instrument, the trip arm will be adjusted to the proper length to hold the receiver hook 70 down in position to disconnect the telephone when the operative end of the trip arm is swung under its pivot screw. The adjustment will be loose enough for the trip arm to swing of its own weight into position 75 over the arm of the receiver hook when the latter is pressed down, the projection on the sleeve 9 by which the trip arm is pivoted being long enough for the trip arm to normally swing well under the bracket when so left to swing free.

After the trip arm is adjusted to hold the receiver hook down, the receiver will be placed in the cradle with the clamping nut 6^a and screw 6 and loose enough so that 85 the receiver may be freely adjusted to properly position it for the particular user. If necessary, the arm 4 may be further bent or slightly straightened to secure the proper adjustment. After the adjustment is secured the clamping screws will be tightened so as to maintain the receiver in fixed position.

When it is desired to use the telephone, all that is necessary is to press the lower end 95 of the trip arm outward. The receiver hook will rise as soon as released and will remain in its upper position with the trip arm resting lightly on it until it is again pressed down. When the conversation is finished, 100 the receiver hook will be pressed down, allowing the trip arm to swing on its own weight into position to hold it down in the manner described.

If the telephone is allowed to remain on 105 the table, the user has both hands free for writing or holding any book or document to be referred to during the conversation, or the telephone may be lifted off the table with one hand, the attachment being 110 stiff enough to maintain the receiver in proper position regardless of the angle at which the telephone is held.

My improved attachment is made applicable to all forms of table telephone instruments which are in use, by the addition to the equipment of a single interchangeable piece which I have shown in use in Figs. 4 and 5. This piece 13 comprises an extension for the receiver hook trip arm to adapt the 120 latter to receive hooks of the type shown in Fig. 4 in which the shank is curved and the only suitable point of engagement for the trip arm is at a distance from the standard of the telephone. In applying the part 125 13 to the bracket the trip arm is removed and the pointed end of the part 13 inserted in the bifurcated projection 9, the slot in the projection 9 extending into the middle of the bracket to receive the pointed end 130

14 of the extension 13 to maintain it in horizontal position. The outer end of the extension 13 is bifurcated to provide the bearing for the trip arm. The operation of the trip arm is obviously the same, whether used with the extension or directly pivoted on the bracket of the attachment.

All other variations in the dimensions, etc. of the telephone instrument will be taken care of by the long range of adjustment of the trip arm in the threaded sleeve 10 and the adjustments of the arm 4 and the supporting cradle for the receiver.

In Figs. 6 and 7 I have shown the attachment modified for use in connection with wall-supported telephones. As here shown, the bracket 15 is attached to the wall adjacent the telephone instrument on the side from which the receiver hook 16 projects.

The bracket consists of two telescoping parts, the outer part 15^a being provided with a fork 17 in which the trip 8^a is pivoted. The trip 8^a is identical in construction with the trip 8 of the desk telephone attachment, and cooperates in the same way with the receiver hook, as will be obvious.

Near the end of the bracket 15 adjacent the wall an elongated vertical bearing 18 is provided in which is swiveled the arm 4^a supporting the receiver, the arm 4^a being in all respects identical with the arm 4. The vertical inner end of the arm 4^a is mounted for vertical as well as horizontal adjustment in the bearing 18, and a set screw 19 is provided for clamping in adjusted position.

Instead of arranging the bracket 15 for attachment to the wall it may be attached directly to the casing of the telephone back of the receiver hook. The operation of this

form of attachment is the same as that of the desk telephone attachment.

I claim:

1. In a telephone attachment the combination of a supporting bracket adapted to be clamped to a telephone standard adjacent the mouth-piece, a sleeve carried by said bracket with the axis of its bore substantially vertical, a receiver-supporting arm having its lower end fitted in said sleeve for both vertical and rotary adjustment, a clamping screw for locking said arm in adjusted position, a receiver-supporting member swiveled on the outer end of said arm for adjustment in a horizontal plane, and a receiver-hook trip also pivoted on said bracket, said hook trip being so designed as to assume automatically when released a position to hold said receiver hook down whereby the telephone will be maintained disconnected upon depressing the receiver hook.

2. In a telephone attachment, the combination of a supporting bracket adapted to be clamped to a telephone standard immediately below the mouth-piece, a receiver-supporting arm connected to said bracket for adjustment in a horizontal plane, a receiver hook controlling trip connected to said bracket and a counterweight also attached to said bracket in position to be on the side of the telephone away from the direction of projection of the receiver-supporting arm when adjusted in position for use.

Signed at New York city, in the county of New York and State of New York, this 75 day of May, 1917.

HENRY J. RICHARDS.
